[57]

CLAIM

The ornamental design for a combined electric ceiling fan and light, as shown and described.

DESCRIPTION

FIG. 1 is a bottom and side perspective view of a combined electric ceiling fan and light, showing my new design;

FIG. 2 is a side elevational view thereof, the opposite side being a mirror image of that shown;

FIG. 3 is a bottom plan view thereof;

FIG. 4 is a bottom and right side perspective view of a combined electric ceiling fan and light showing a second embodiment of my new design;

FIG. 5 is a side elevational view of FIG. 4, the opposite side being a mirror image of that shown;

FIG. 6 is a bottom plan view of FIG. 4;

FIG. 7 is a bottom and side perspective view of a combined electric ceiling fan and light showing a third embodiment of my new design;

FIG. 8 is a side elevational view of FIG. 7, the opposite side being a mirror image of that shown;

FIG. 9 is a bottom plan view of FIG. 7;

FIG. 10 is a bottom and side perspective view of a combined electric ceiling fan and light showing a fourth embodiment of my new design;

FIG. 11 is side elevation view of FIG. 10, the opposite side being a mirror image of that shown;

FIG. 12 is a bottom plan view of FIG. 10;

FIG. 13 is a bottom and side perspective view of a combined electric ceiling fan and light showing a fifth embodiment of my new design;

FIG. 14 is a side elevation view of FIG. 13, the opposite side being a mirror image of that shown;

FIG. 15 is a bottom plan view of FIG. 13;

FIG. 16 is a bottom and side perspective view of a combined electric ceiling fan and light showing a sixth embodiment of my new design;

FIG. 17 is a side elevation view of FIG. 16, the opposite side being a mirror image of that shown;

FIG. 18 is a bottom plan view of FIG. 16; and,

FIG. 19 is a top plan view of the first through sixth embodiments of the invention shown in FIGS. 1-18; the ceiling fan canopy, constituting the top most portion of the fan which is illustrated, mounts flush against the ceiling when the fan is in use, and only when the fan is detached is it possible to view the fan from the top as shown in FIG. 19.

UNITED STATES PATENT AND TRADEMARK OFFICE
CERTIFICATE OF CORRECTION

PATENT NO. : Des. 328,785

Page 1 of 9

DATED : August 18, 1992

INVENTOR(S) : Michael A. Markwardt

It is certified that error appears in the above-identified patent and that said Letters Patent is hereby corrected as shown below:

The title page showing the illustrative figure should be deleted to be substituted with the attached title page.

In the drawings, delete sheets 1 through 7 (Figs. 1-19) and substitute the attached sheets 1 through 7.

Signed and Sealed this
Ninth Day of August, 1994

Attest:

Attesting Officer

BRUCE LEHMAN

Commissioner of Patents and Trademarks
